COMBINED TRACK GAUGE CONTROL DEVICE AND TRAIN STOPPING DEVICE

Original Filed Oct. 1, 1925

UNITED STATES PATENT OFFICE

HEINRICH KARL, OF JERSEY CITY, NEW JERSEY

COMBINED TRACK GAUGE CONTROL DEVICE AND TRAIN STOPPING DEVICE

Original application filed October 1, 1925, Serial No. 59,917, and in Germany June 24, 1927. Divided and this application filed October 26, 1927. Serial No. 228,868.

This invention formed part of my pending patent application, Serial No. 59,917 that was filed October 1, 1925, and of which division was required according to the Examiner's communication of December 4, 1925.

This invention relates more particularly to a system in which the gauge of the entire track of a railroad line or trolley line, etc. can be controlled automatically and this control 10 performed by a special truck or some unit of a train that is equipped with said device.

One object of this invention is to bring said device in connection with an automatic train stopping device so that a train equipped therewith will be braked or stopped automatically before a derailment occurs, or it will avoid disaster to a fast moving train of which some unit might have been derailed already following the moving of the train on a 20 part of the trackway that has abnormal gauge.

Another object of the invention is to render this system completely safe and, therefore, it is designed on the principle of the normally 25 closed electric circuit.

A further object is to create a signal, audible or visible, or both, and a device for making the signalling therethrough continuously, should that train move on such track rails 30 that have abnormal gauge.

A further object is to create means for discontinuing the stopping of the train and said signalling.

Although only one embodiment is exemplified in this invention, it can be brought in connection with any automatic train control system, or it may be so devised as to be independent of it and to cause the display of a signal on the train or on a special truck, and it 40 may be so designed as to cause the automatic stopping of the train or trolley car, etc., or to cause only the reduction of the speed thereof if that special truck or train unit moves on rails that have not the normal gauge or that 45 may be spread or inwardly inclined.

This invention is hereinafter described in detail and the novelty pointed out in the appended claims and is illustrated by the accompanying drawings of which—

Figure 1 shows a side view of the device

and part of a car or truck to which it is connected and said car or truck is coupled to a locomotive of which only a fraction is shown;

Figure 2 is another view of the device that is connected to the car or truck whereby parts are shown in section to permit the viewing of the mechanism;

Figure 3 is a top view of the device and a diagram of electric connections that serve for making audible or visual signals and for bringing the train to a stop in case of an abnormality in the gauge of the track rails.

Figure 4 shows in section a modification of the center part of the device shown in Figure 2 whereby arrangements are shown for exerting the flexible pressure through compressed air instead of the spring 8 of Figure 2.

The wheels 1 and 2, which are of light construction since there will not be any weight of the car or truck 10 that bears upon them, each has its special shaft or axle 3, 4 respectively, and at their inner ends these axles are provided with piston-like parts 5, 6 respectively, of insulating material. These parts 5

and 6 and part of the axles 3 and 4 are confined in a cylindrical body 7 that is made in part of insulating material and having one or more ribs 7a on its outer surface for preventing it from revolving. The ends of this tube 70 or cylindrical body 7 form bearings made of metal that serve for the axles 3, 4 respectively. Between the parts 5 and 6 a spring 8 of certain flexibility is arranged and between the spring and the parts 5, 6 plates of metal 5a, 6a 75 may be placed. Instead of the spring 8, however, compressed air may be used. The use of compressed air may be preferable to that of the spring 8 because the spring is liable to be worn out or parts in connection therewith, 80 and since there is continuous supply of compressed air on trains for the operation of the brakes the simplest arrangement is then that as shown in Fig. 4 in which a pipe 101 is connected to the train pipe and also to the tube 7.

It is thus shown that through the communication of the train pipe 100 with the space 102 between the two discs 5a' and 6a' compressed air enters that space and exerts pressure upon said discs and consequently 85 90 95 100

also upon the piston-like parts 5' and 6' which are exactly like those indicated by 5 and 6 in Fig. 2.

In order to prevent the pressure in said space 102 between the discs 5a' and 6a' from becoming too weak when there will be a reduction in pressure in the train pipe 100 an automatic valve 103 well known in the art is brought in connection with pipe 101. A spring 104 is arranged around the stem 105 of valve 103 and so placed in the perforated extension 101' that it presses the valve plug 103' immediately against the opening at the lower end of pipe 101 so that said pipe will be hermetically closed when the pressure in the train pipe and consequently in pipe 101 becomes so low that there will not be enough pressure exerted upon the valve plug 103. The pressure in space 102 thus will not be reduced. It may happen, however, that a too strong pressure will be exerted upon the discs 5a' and 6a' which is not desirable neither and in order to prevent an excessive pressure of the compressed air in space 102 a relief-valve 106 is arranged. This valve is also of the plug type and a spring 107 that is arranged around the stem 108 of the valve plug 106' presses against the plug 106' and the lower end wall of the extension 109 and forces thereby the valve plug 106' to close the aperture 110 at the upper end of the extension 109. Spring 107 must therefore yield only to an excessive pressure in which case the plug 106' will be pressed downward against the pressure of the spring 107 so that a quantity of compressed air can escape through the channel 111 whereupon spring 107 pushes the plug 106' against the upper end wall of the extension 109 in which the opening 110 is left whereby that opening will be closed again when the pressure in space 102 has become normal. The other structural parts in connection with tube 7' are exactly alike to those illustrated in Fig. 2 in connection with tube 7 and for this reason no illustration thereof has been deemed necessary and further reference is therefore made to Fig. 2 instead of Fig. 4. On one of the axles such as indicated by 3, an annular electric contact 14 is arranged that normally contacts with the electric contact 11 that is somewhat flexibly arranged on the tube 7. The axle 4 has an abutment or stop 12 that prevents the axle from moving further into the tube 7 and another stop 13 on axle 4 that like stop 12 adjoins bearing 15a but inside the tube prevents the axle 4 from moving further outside the tube. These or similar stops, however, are not employed in connection with the axle 3 and it is therefore apparent that the spring 8 will, by exerting pressure against the plate 5a of part 5, move the axle 3 outwardly should the rail 20 or the rail 21 be bent or inclined outwardly as shown in Figure 2, because in that event the wheel 1 whose flange, is always in

contact with the inner side of the rail-head on account of the pressure exerted by the spring 8, moves therefore also the axle 3 outwardly whereby the contact 14 will be separated from the contact 11 when the rail 20 or 21 becomes inclined or moved outwardly to a certain extent. 70

In the case where rail 21 is spread or inclined or moved outwardly, the flange of wheel 2, however, will remain in contact with the rail-head of rail 21 because wheel 1 whose flange is pressed against the inner side of the rail-head of rail 20 makes counter pressure and axle 3 with piston 5, and plate 5a exert this pressure upon the spring 8; spring 8 again presses against plate 6a and moves thereby piston 6, axle 4 and wheel 2 towards the left according to the view of Figure 2. The flange of wheel 2 is therefore forced to contact with the head of the spread rail 21. 80 The tube 7 is also forced to make that move to the left because stop 13 that is firmly united with the axle 4 pushes then against the bearing 15a which is firmly united with the tube 7. Also in this case will contact 14 be separated from contact 11 and take a position as illustrated in Figure 2. If, however, the inclination or moving of the rail 20 or 21 happened in the inverse direction, that is, inwardly, then the wheel 1 will be forced to be nearer to the bearing 15 because the distance between the two rail-heads is smaller, wheels 1 and 2 are therefore brought nearer to each other whereby spring 8 becomes more compressed and consequently the axle 3 that is rigidly united with the wheel 1 will also be moved further into the tube 7 whereby the contact 14 will also come out of contact with the contact 11 and will take a position that is on the left of contact 11 according to the view of Figure 2. The tube 7 is held by springy bands 16, 17 that are fastened to a log 18 which again is held by braces 19, 19a which are rigidly united with the wheel frame of the truck wheels 22, 23. The springy bands 16, 17, however, are not fastened to the tube 7, they simply surround it partly but hold it loosely so that the tube 7 is allowed to move lengthwise to a certain extent to the right or left within the bent portion of the springy bands 16, 17 when the truck 10 moves along a curve etc. Ribs 7a (see Figure 1) being longitudinally arranged on the outer side of tube 7 are provided for to prevent the revolving of this tube while the wheels 1 and 2 roll along the track rails and the springy bands 16, 17 are bent so as to hold the ribs when the tube 7 would otherwise start to revolve. 90

The truck 10 to which belong the truck wheels 22, 23 may be any regular truck or car that forms one of the train units. Truck 10, however, may as well be a special truck that serves only the purpose for carrying wheels 1 and 2 and associated mechanism and therefore need to have only the two truck 100

wheels 22, 23 and this truck may be coupled so to the locomotive that it travels at the head of the train such as exemplified in Figure 1.

8 The part of the invention that causes the stopping of the train and the signalling to the engineer in case that there is an abnormality in the gauge of the track is of an electrical character and is chiefly illustrated in Figure 3.

10 Owing to the fact that an abnormality of the gauge of the trackway may take place at any time, it is advisable that every train be equipped with said device and as the 15 danger exists that the whole train or some units thereof will derail at the same moment in which the train moves on rails that are spread or moved inwardly etc., it is of importance that the train then be braked instantly for avoiding disaster. But the fact 20 that it cannot be relied upon the alertness of the engineer, it is necessary that such needed rapid action of applying the brakes be made automatic and one of the simplest but very 25 safe systems is described hereinafter.

Connected to the bearing 15 which may be made of brass or copper (or it may be a special connection) there is a wire 26 (see Figures 2 and 3) which wire is also connected to 30 one end of the winding of the electromagnet 204. To the other end of that winding is connected the wire 206 which leads to the positive side of battery 25. To the negative side of battery 25 is connected the wire 28 35 which by its other end is connected to one of the ends of the winding of relay 27 that serves in the signalling system of the invention to be described later. Connected to the other end of the winding is the wire 30 which 40 is again in electric connection with contact.

11. By adding the contact 14 and axle 3 a circuit is created which I will term circuit *a*.

Whenever the contact 14 becomes disengaged from the contact 11 on account of an 45 abnormality in the gauge of the track the circuit *a* will be interrupted and the electromagnet 204 that forms part of an electromagnetic venting device becomes de-energized. The result is a venting of the train 50 pipe and a stopping of the train as will be briefly pointed out hereinafter.

By the reference numeral 224 is indicated the train pipe that is shown in section. Connected to this train pipe 224 is a short pipe 55 226 and a valve 225 is seated in pipe 226. To the valve 225 is connected a lever 230. The upper end of this lever is provided with a weight 231c that is so arranged that it will be attracted by gravity and thereby tend to 60 turn always the lever 230 so as to move the valve 225 to open position and to thereby free the compressed air in the train pipe 224. For holding the valve in the closed position and again for moving it to open position for 65 permitting the exhaust of air from the train

pipe in well dosed portions according to the needs for braking the train, the electromagnet 204 is employed whose core is attached to the lower end of the lever 230. If electro-magnet 204 is fully energized the core 70 thereof will be fully attracted and the lever 230 will resume the vertical position in which it moves the valve 225 to closed position whereby no compressed air can escape from the train pipe 224. A very weak energization of electro-magnet 204, however, or a complete de-energization renders electro-magnet 204 powerless against the pressure of the weight 231c that is attracted by gravity and the lever 230 will be turned so as to 80 move the valve 225 to open position whereby compressed air can freely escape to the atmosphere (or to a suitable reservoir) which, as known, causes the application of the brakes and a quick stop which is termed an 85 emergency application.

A lock 230c is to be employed to hold the lever 230 in the inclined position that it resumes at the de-energization of electromagnet 204 whereby the valve 225 would remain 90 in its open position even after the re-energization of electromagnet 204. Only through the release of the lever 230 through the manually performed unlocking would then the valve 225 be turned to closed position. The 95 unlocking is performed by pushing lock bolt 230c against the spring 230d.

It may be desirable to have also a signalling means in connection with the track gauge control device that promptly will signal the 100 engineer when there is a dangerous abnormality in the gauge of the track so that the engineer will also know right away the cause of the automatic emergency application of the train brakes.

105 A preferable form of such signalling means is shown in Figure 3 and is brought in connection with circuit *a* which includes the winding of relay 27.

If the relay 27 becomes de-energized its 110 armature or contact 40 comes into contact with a contact 41 and a circuit will be closed thereby which I will term the circuit *d*. In this circuit are included: battery 25, wire 42 that must have a resistance 43 of a certain 115 amount of ohms, electric bulb 44, wire 45, bell 46, wire 47, contact 41, armature 40, wire 48 and battery 25. According to desirability only the electric bulb 44 or only the bell 46 may be used and included in the 120 circuit. In order to prevent the armature 40 from being moved to its uppermost position and therefore disconnected from the contact 41, which might take place immediately after it is dropped upon contact 41 because 125 contact 14 will come again into contact with contact 11 while the wheels 1 and 2 move on rails that have the normal gauge whereby circuit *a* will be closed, the spring 50 is used 130 that serves as a holder and is so arranged that

its free end will be pushed down when the armature 40 drops, but as it is not long enough to be kept down when the armature 40 rests upon the contact 41 the free end of spring 50 darts back but is held up by a stop 51, and in this position the free end of spring 50 holds fast the armature whose end part may be so formed that the spring will have a hold on it. Through this simple device a continuous ringing of the bell 46 and continuous burning of the light 44 is obtained that signals the engineer of the fact that there is an abnormality in the gauge of the track that caused also the emergency application of the brakes.

For stopping the ringing of the bell and for discontinuing the burning of the lamp 44 the free end of spring 50 must be pulled down so that the armature 40 will not be hindered to move to its upper position when relay electro-magnet 27 is energized again. If this relay 27 should be situated at a place that might not be very well accessible a rope 52 may be attached to the free end of spring 50 and a ring or handle 53 secured to the other end thereof with which to pull down that free end of the spring 50.

Track gauge control devices for merely signalling abnormalities in the gauge of the track are known already in the art, but those belonging to that class that are adapted to move along the whole trackway for detecting abnormalities in the gauge thereof are designed on the normally open circuit which, however, is not completely reliable.

There may be employed a special truck 10 that will not be part of a train and that is equipped with self-propelling means such as a motor (electric or otherwise) and serving simply for moving along the railroad lines for detecting abnormalities of the gauge of the track.

Having described a preferable form of my invention, I wish to make it known that many modifications thereof are possible which, however, may be all in the spirit and scope of this invention; such modifications may be made especially with normally open circuit arrangements while this invention is devised chiefly on the principle of the normally closed circuits.

I claim:

1. In a device for controlling the gauge of the track combined with a train stopping device, two electric contacts arranged on this device, normally contacting each other and comprised in an electric circuit which they keep closed when contacting each other, said track gauge controlling device belonging to that type in which two wheels with flanges are employed, one of which is adapted to be always in contact with the rail-head of the left-side rail of the track when moved along said track and the other adapted to be always in contact with the rail-head of the

right-side rail of said track, two piston-like parts arranged in a tube, one of these parts connected to a shaft of one of said wheels and the other connected to another shaft of the other wheel, and compressed fluid introduced between said piston-like parts to exert pressure upon them and thereby keep said wheels always in contact with their respective rail-heads also whenever the gauge of the track becomes abnormal, said two electric contacts, however, being so arranged that they will be separated whenever said two wheels become more distanced from each other or when they approach each other more than they will do when the gauge of the track is normal, a train control mechanism controlled by said circuit and rendered effective when said circuit will be opened, and a signalling means so arranged that it will then become also effective.

2. In a system for controlling the gauge of the track combined with a brake controlling device, a train and an automatic control device thereon, a normally closed circuit in connection with brake-controlling devices adapted to stop the train when said circuit is opened, a train unit adapted to travel at the head of the train and having a pair of wheels of lighter construction than the truck wheels thereof, a tube and a flexible fluid confined therein, a shaft united with one of said wheels of light construction and a part of said shaft thrusting against said flexible fluid when these wheels of light construction are engaged by the track rails, whereby said wheels of light construction therefore will reduce and will also increase the distance between each other according to the abnormalities in the gauge of the track, an electric contact arranged so as to contact with a second electric contact on said shaft when the gauge of the track is normal and thereby forming a closed connection in said circuit, and this contact being so formed as to become disconnected from the electric contact on said shaft when said wheels of light construction move outwardly or inwardly according to the abnormal condition of the gauge of the track, thereby causing an application of the brakes following the opening of said circuit.

3. In a system for controlling the gauge of the track combined with a train stopping device, the combination of a railroad line and a train to travel thereon, an automatic train control device on the train, a normally closed circuit for controlling brake control devices on the train, a train unit, means on said train unit for controlling the gauge of the track while it is travelling, two electric contact means so arranged within said means for controlling the gauge of the track as to contact with each other and keeping said circuit closed when the gauge of the track is normal and said electric contact means separating from each other and causing the opening of

said circuit and consequently the effective control of the train when the gauge of the track becomes abnormal.

4. In a system for controlling the gauge of the track combined with a train stopping device, the combination of a railroad line, a train and an automatic control device thereon, a normally closed circuit in connection with brake-controlling devices adapted to 10 stop the train when said circuit is opened, a train unit adapted to travel at the head of the train and having the known pair of wheels serving in connection with other means for the control of the gauge of the 15 track while rolling along the rails, two electric contacts arranged within said other means for controlling the gauge of the track, contacting with each other and keeping thereby said circuit closed when said pair of wheels 20 move on rails where the gauge of the track is normal and said electric contacts separating themselves and opening said circuit when said wheels move on rails where the gauge of the track is abnormal.
